PAIR OF SPECTACLES

Peter J. Morroni, Leominster, Mass.

Application June 7, 1955, Serial No. 36,418

Term of patent 3½ years

(Cl. D57—1)

FIG. 2

FIG. 3

Fig. 1 is a top plan view of a pair of spectacles, showing my new design;

Fig. 2 is a front elevation view thereof; and

Fig. 3 is a side elevation view thereof.

The rear surface of the spectacle frame is plain.

I claim:

The ornamental design for a pair of spectacles, as shown and described.
